CLAIM

The ornamental design for a tank toy, as shown and described.

DESCRIPTION

FIG. 1 is a front perspective view of a tank toy showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is another perspective view thereof.

The broken lines in the drawings depict portions of the tank toys that form no part of the claimed design.
